UNITED STATES PATENT OFFICE

EASTON E. PARRILL, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY SIGNALING

Application filed October 18, 1929. Serial No. 400,542.

My invention relates to railway signaling, and particularly to manually controlled signaling for stretches of single track railway. One feature of my invention is the provision 5 of complete automatic traffic locking between control stations without the necessity for line wires.

I will describe one form of system embodying my invention, and will then point out the 10 novel features thereof in claims.

The accompanying drawing is a diagrammatic view showing one form of system embodying my invention.

Referring to the drawing, the reference 15 characters 1 and 1^a designate the track rails of a stretch of single track railway along which traffic moves in both directions. These rails are divided by insulated joints 2 to form a main section X—Y, as well as an approach 20 section U—X at one end of the main section, and another approach section Y—V at the other end of the main section.

Each approach section is provided with a track circuit comprising a battery 27, and a 25 track relay designated by the reference character T with an exponent corresponding to the location.

Eastbound traffic through the stretch U—V is governed by a signal S^U, having a main 30 arm 21 and a calling-on arm 22. Westbound traffic through this stretch is governed by a similar signal S^V, having a main arm 23 and a calling-on arm 24.

Each end of the main section X—Y is provided 35 with a manually operable lever designated by the reference character L with an exponent corresponding to the location. Each of these levers has a normal position N, a reverse position R, and a middle or central 40 position C.

Also located adjacent each end of the main section X—Y, is a stick relay R, a track battery C, a track relay T, and a home stick relay Q.

Referring particularly to stick relay R^X, this relay is provided with a pick-up circuit which passes from terminal B of a suitable 45 source of current, through a normal contact L^X_N of lever L^X, a front contact 17 of the track relay T^U for section U—X, and the

winding of relay R^X, to terminal O of the same source of current. This relay is also provided with a stick circuit which includes a front contact 9 of the relay itself, but excludes the front contact 17 of track relay T^U. 55 The circuits for relay R^Y are similar to those for relay R^X. It follows that each relay R is normally energized.

Each track battery C is normally connected across the rails of the section X—Y. Referring to battery C^X, for example, the circuit is from the upper terminal of this battery, through back contact 18 of relay Q^X, front contact 10 of relay R^X, to track rail 1^a, and from track rail 1, through back contact 60 5 of track relay T^X to the lower terminal of battery C^X.

Each track relay T is normally disconnected from one of the track rails at back contact 10 or 14 of relay R^X or relay R^Y. Each 65 relay Q^X and Q^Y is normally de-energized, because its circuit is open at contact 3 of track relay T^X or contact 6 of track relay T^Y, as well as at the contacts of the associated levers as 70 will appear hereinafter.

The operation of the apparatus is as follows: I will first assume that the operator at point X desires to admit an eastbound train to section X—Y. To do this, he will move 75 lever L^X to the R position, thereby opening at contact L^X_N both the pick-up and the stick circuits for relay R^X, so that the latter relay will become de-energized. The closing of the

back point of contact 10 of relay R^X will connect track relay T^X with the track rails, so 80 that this relay will become energized. A pick-up circuit for relay Q^X will then be closed, which circuit passes from terminal B, through a lever contact L^X_{CR}, front contact 3 of track relay T^X, and the winding of relay 85 Q^X to terminal O. A stick circuit for relay Q^X will then be closed, which circuit passes from terminal B, through another lever contact L^X_{RC}, front contact 11 of relay Q^X, and the winding of relay Q^X to terminal O.

It follows that relay Q^X will then remain energized as long as lever L^X remains in either the R or the C position or any position between the two. The closing of relay Q^X will 90 close a circuit for arm 21 of signal S^U, which 95 100

circuit passes from terminal B, through lever contact L^x_R , front contact 12 of relay Q^x , front contact of push button P^x , front contact 4 of track relay T^x , front contact 25 on track relay T^u , and the operating mechanism of signal arm 21 to terminal O. As soon as this arm moves to the clear position, a second stick circuit for relay Q^x will become closed, which circuit passes from terminal B, through contact 21° operated by signal arm 21, front contact 11 of relay Q^x , and the winding of relay Q^x to terminal O. When the train enters section U—X, it will open track relay T^u , and this will open the circuit for signal arm 21 so that the arm will return to the stop position. When the train enters section X—Y, it will cause track relay T^x to become de-energized, thereby opening the circuit for signal arm 21 at contact 4, so that this arm will remain in its stop position. Relay Q^x will remain energized, however, because of its stick circuit through lever contact L^x_{RC} . When the train passes out of section X—Y, signal arm 21 will return to its clear position, provided, of course, that lever L^x remains in its R position. It follows that any desired number of eastbound trains may be allowed to pass through the section X—Y without the necessity for further manipulation of lever L^x . If the operator desires to place signal S^u at stop without disturbing the locking, he may do so by moving lever L^x to the C position. This will open the circuit for signal S^u at lever contact L^x_R , but it will not open the stick circuit for relay Q^x . Signal S^u may then be cleared again by merely moving lever L^x back to its R position.

I will now assume that while section X—Y is occupied by a train moving toward the east, the operator desires to admit a second eastbound train to this section. To do this, he will leave lever L^x in the reverse position and will depress push button P^x , thereby closing a circuit for the calling-on arm 22 of signal S^u . This circuit is from terminal B, through lever contact L^x_R , front contact 12 of relay Q^x , lower contact of push button P^x , and the operating mechanism of signal arm 22 to terminal O. A third stick circuit for relay Q^x will then be closed, which circuit includes contact 22° which is operated by signal arm 22 and is closed when this arm is in the clear position. It follows that arm 22 will remain in the clear position until lever L^x is returned to its normal position.

The operation of the apparatus for admitting westbound trains into section X—Y will be apparent from the foregoing discussion without detailed explanation.

Reverting to the operation required for the clearing of signal S^u , it will be noted that track relay T^x must be energized from battery C^x at the east end of section X—Y. The circuit for this battery passes through contact 20 of relay Q^y , thereby assuring that

both arms of signal S^v are in the stop position before signals S^u can be cleared. The circuit for battery C^y also passes through front point of contact 14 of relay R^y , thereby providing a check that lever L^y is in the normal position. The circuit for battery C^y also includes a back contact 8 of track relay T^y , thus insuring that this relay is de-energized before relay T^x can become energized. Furthermore, if section Y—V is occupied by a westbound train and lever L^y has been reversed, then a restoration of this lever to normal position will not permit signal S^u to be cleared because the pick-up circuit for relay R^y will be open at track relay contact T^y_{10} and so relay R^y cannot be energized to apply battery C^y to the track rails.

It will be seen from the foregoing that I have provided all that is necessary in the way of locking to prevent the clearing of opposing signals, and have at the same time provided for the clearing of signals to allow for following moves, and that this is all accomplished by the use of the track rails without the necessity for line wires extending from control station to control station.

Although I have herein shown and described only one form of system embodying my invention, it is understood that various changes and modifications may be made therein within the scope of the appended claims without departing from the spirit and scope of my invention.

Having thus described my invention, what I claim is:

1. In combination, a stretch of railway track made up of a main section and an approach section at each end of the main section, a track circuit including a track relay for each approach section, a track battery and a track relay at each end of said main section, two relays R and Q at each end of said main section, a manually operable lever at each end of said main section and each having a normal and a reverse position, two signals governing traffic in opposite directions through said stretch, a pick-up circuit for each relay R closed when the associated lever is in the normal position and the track relay for the associated approach section is energized, a stick circuit for each relay R closed when the relay is energized and the associated lever is in normal position, means operating to connect each main section track battery with the rails of the section when the associated relay R is energized provided the associated relay Q and the associated track relay are de-energized, means operating to connect each main section track relay with the rails of the section when the associated relay R is de-energized, a pick-up circuit for each relay Q closed when the associated lever is in the reverse position and the associated main section track relay is energized, means for clearing each signal when the associated

track relay and the associated relay Q are energized and the associated lever is in the reverse position, and a stick circuit for each relay Q including a contact closed when the associated signal indicates proceed.

- 5 2. In combination, a stretch of railway track made up of a main section and an approach section at each end of the main section, a track circuit including a track relay for each approach section, a track battery and a track relay at each end of said main section, two relays R and Q at each end of said main section, a manually operable lever at each end of said main section and each having a normal and a reverse position, two signals governing traffic in opposite directions through said stretch, means for energizing each relay R when the associated lever is in the normal position and the associated approach section track relay is energized and for subsequently keeping relay R energized as long as the lever remains in normal position, means for connecting each main section track battery with the rails of the section when the associated relay R is energized provided the associated relay Q and the associated track relay are de-energized, means for connecting each main section track relay with the rails when the associated relay R is de-energized, means for energizing each relay Q when the associated main section track relay is energized and the associated lever is in reverse position, and means for controlling each signal jointly by the associated lever, main section track relay, and relay Q.
- 10 3. In combination, a stretch of railway track made up of a main section and an approach section at each end of said main section, a track battery and a track relay at each end of said main section, two relays R and Q at each end of said main section, a manually operable lever at each end of said main section and each having a normal and a reverse position, means for energizing each relay R when the associated approach section is unoccupied and the associated lever is in normal position and for subsequently keeping relay R energized until the lever is reversed, means for connecting each main section track battery with the rails of the section when the associated relay R is energized provided the associated relay Q and the associated track relay are de-energized, means for connecting each main section track relay with the rails when the associated relay R is de-energized, means for energizing each relay Q when the associated main section track relay is energized and the associated lever is in reverse position, and means for controlling each signal jointly by the associated lever, main section track relay, and relay Q.
- 15 4. In combination, a stretch of railway track made up of a main section and an approach section at each end of said main section, a track circuit including a track relay for each approach section, a track battery and a track relay at each end of said main section, two relays R and Q at each end of said main section, a manually operable lever at each end of said main section and each having a normal and a reverse position, signals governing traffic in opposite directions through said stretch, and means for clearing each signal when the associated lever is reversed provided the associated track relay and relay Q are energized, and means for keeping each relay Q energized as long as the associated lever is reversed.
- 20 5. In combination, a stretch of railway track made up of a main section and an approach section at each end of said main section, a track circuit including a track relay for each approach section, a track battery and a track relay at each end of said main section, two relays R and Q at each end of said main section, a manually operable lever at each end of said main section and each having a normal and a reverse position, signals governing traffic in opposite directions through said stretch, and means for clearing each signal when the associated lever is reversed provided the associated track relay and relay Q are energized, and means for keeping each relay Q energized as long as the associated lever is reversed.
- 25 6. In combination, a stretch of railway track made up of a main section and an approach section at each end of said main section, a track circuit including a track relay for each approach section, a track battery and a track relay at each end of said main section, two relays R and Q at each end of said main section, a manually operable lever at each end of said main section and each having a normal and a reverse position, as well as a middle position, two signals governing traffic in opposite directions through said stretch, a pick-up circuit for each relay R

track made up of a main section and an approach section at each end of said main section, a track battery and a track relay at each end of said main section, two relays R and Q at each end of said main section, a manually operable lever at each end of said main section and each having a normal and a reverse position, means for energizing each relay R when the associated approach section is unoccupied and the associated lever is in normal position and for subsequently keeping relay R energized until the lever is reversed, means for connecting each main section track battery with the rails of the section when the associated relay R is energized provided the associated relay Q and the associated track relay are de-energized, means for connecting each main section track relay with the rails when the associated relay R is de-energized, means for energizing each relay Q when the associated main section track relay is energized and the associated lever is in reverse position, signals governing traffic in opposite directions through said stretch of track, means for clearing each signal when the associated lever is reversed provided the associated track relay and relay Q are energized, and means for keeping each relay Q energized as long as the associated lever is reversed or the associated signal is clear.

70 7. In combination, a section of railway track, a track battery at each end of the section normally connected with the rails, a track relay at each end of the section normally disconnected from the rails, a manually operable lever at each end of the section having a normal and a reverse position, means responsive to reversal of each lever for disconnecting the associated battery from and connecting the associated track relay with the rails of the section, a normally de-energized stick relay Q at each end of said section, means for energizing each relay Q when the associated lever is reversed and the associated track relay is energized, signals governing traffic in opposite directions through said section, means for clearing each signal when the associated lever is reversed provided the associated track relay and relay Q are energized, and means for keeping each relay Q energized as long as the associated lever is reversed or the associated signal is clear.

75 8. In combination, a stretch of railway track made up of a main section and an approach section at each end of said main section, a track circuit including a track relay for each approach section, a track battery and a track relay at each end of said main section, two relays R and Q at each end of said main section, a manually operable lever at each end of said main section and each having a normal and a reverse position, as well as a middle position, two signals governing traffic in opposite directions through said stretch, a pick-up circuit for each relay R

closed only when the associated lever is in the normal position and the track relay for the associated approach section is energized, a stick circuit for each relay R closed only when the relay is energized and the associated lever is in normal position, means operating to connect each main section track battery with the rails of the section when the associated relay R is energized provided the associated relay Q and the associated track relay are de-energized, means operating to connect each main section track relay with the rails of the section when the associated relay R is de-energized, a pick-up circuit for each relay Q closed when the associated lever is in the reverse or the middle position and the associated main section track relay is energized, a stick circuit for each relay Q closed when the relay is energized and the associated lever is in the reverse or middle position, means for clearing each signal when the associated track relay and the associated relay Q are energized and the associated lever is in the reverse position, and a second stick circuit for each relay Q including a contact closed when the associated signal indicates proceed.

7. In combination, a stretch of railway track made up of a main section and an approach section at each end of said main section, a track battery and a track relay at each end of said main section, two relays R and Q at each end of said main section, a manually operable lever at each end of said main section and each having a normal and a reverse position as well as a middle position, means for energizing each relay R when the associated approach section is unoccupied and the associated lever is in normal position and for subsequently keeping relay R energized until the lever is moved away from its normal position, means for connecting each main section track battery with the rails of the section when the associated relay R is energized provided the associated relay Q and the associated track relay are de-energized, means for connecting each main section track relay with the rails when the associated relay R is de-energized, means for energizing each relay Q when the associated main section track relay is energized and the associated lever is in its reverse or middle position, signals governing traffic in opposite directions through said main section, means for clearing each signal when the associated lever is in the reverse position provided the associated track relay and relay Q are energized, and means for keeping each relay Q energized as long as the associated lever is in its reverse or its middle position.

8. In combination, a section of railway track, a track battery at each end of the section normally connected with the rails, a track relay at each end of the section normally disconnected from the rails, a manually operable lever at each end of the section having a nor-

mal and a reverse position as well as a middle position, means responsive to reversal of each lever for disconnecting the associated battery from and connecting the associated track relay with the rails of the section, a normally de-energized stick relay Q at each end of said section, means for energizing each relay Q when the associated lever is reversed and the associated track relay is energized, signals governing traffic in opposite directions through said section, means for clearing each signal when the associated lever is in the reverse position provided the associated track relay and relay Q are energized, and means for keeping each relay Q energized as long as the associated lever is in either its reverse or its middle position.

In testimony whereof I affix my signature.
EASTON E. PARRILL.
